SMOKING PIPE

John Lang, New York, N. Y.

Application October 11, 1939. Serial No. 298,950

1 Claim. (Cl. 131—181)

This invention relates to an improved smoking pipe and has for an object to provide a construction wherein means are provided for urging the tobacco toward the fire.

5 Another object of the invention is to provide a smoking pipe wherein the bowl of the pipe is loaded at the usual end and means provided which will continually urge the tobacco toward the loading or entrance end so that the tobacco 10 is moved toward the fire instead of the fire toward the tobacco.

An additional and more specific object is to provide a pipe having a tobacco chamber and spring-actuated means for urging the tobacco toward the 15 entrance end of the bowl so that during the smoking operation the tobacco will be gradually moved toward the fire whereby a minimum amount of ashes falls to the bottom of the pipe bowl.

In the accompanying drawing—

20 Fig. 1 illustrates a pipe embodying the invention, the bowl portion being shown in vertical section;

Fig. 2 is a longitudinal vertical section through a slightly modified form of pipe to that shown in 25 Fig. 1;

Fig. 3 is a sectional view through the cap or entrance end member shown in Fig. 2;

Fig. 4 is a front view of the structure shown in Fig. 3.

30 Referring to the accompanying drawing by numerals, 1 indicates the bowl of the pipe, which bowl merges into a stem 2 having a mouthpiece 3 of any usual or preferred structure. The smoking pipe may be made to represent a conventional pipe, as shown in Fig. 1, or may be made to represent a cigar or other smoking article, as shown in Fig. 2. It will, therefore, be understood that the expression "smoking pipe" will refer to both forms of the invention or any other embodiment thereof 35 wherein the same principles are used.

40 As illustrated in Fig. 1, the bowl 1 is provided with a body 4 that has a closed end 5 merging into a stem 2. The parts just described may be made of briar root or other suitable material, but the 45 entrance end member or portion 6 is made of substantially fire-proof material, as for instance, metal or meerschaum. The entrance end portion 6 is provided with a threaded part 7 screwed into the offset threaded part 8 of the body 4. The 50 member 6 is provided with an annular inturned flange portion 9 which results in the formation of an entrance end opening 10 through which the tobacco is inserted into the chamber 11. As shown in Fig. 1, the tobacco 12 completely fills the chamber 11 and extends from the entrance 55

opening 10 to the follower plate 13. This plate may be of any foraminous material, as for instance, it may be a perforated metal plate having an annular depressed portion 14 and a flange portion 15, which flange portion is provided with an annular bevel 16. The end of the bevel is very near the side wall of the chamber 11 but as the tobacco is consumed the coil spring 17 forces the plate 13 upwardly or toward the entrance end 10 and as the plate 13 moves it will allow small 10 particles of the tobacco or ashes to pass. The coil spring 17 has one end or end portion resting on the bottom 18 of the tubular socket 19 while the other end surrounds the depressed portion 14. The spring 17 is preferably formed sufficiently 15 strong to push the plate 13 and the tobacco upwardly as fast as the tobacco is consumed at the entrance end 10. Also preferably the spring 17 is sufficiently long to force plate 13 up to within a short distance of the entrance end of the pipe. 20

By this construction and arrangement the tobacco moves toward the zone of fire rather than the zone of fire moving toward the tobacco. This has a tendency to keep the bottom part of the chamber clean of saliva and other deposit. Any 25 ashes or tobacco falling down past the beveled edge 16 may be readily removed by turning the pipe upside down and striking the same against an object. If desired, the end member 6 may be unscrewed and plate 13 removed for a thorough 30 cleaning. The parts may then be replaced and after this has been done tobacco may be forced in through the end member 10. As the tobacco is forced into the chamber 11, the plate 13 begins to move downwardly toward the closed end 5 until the parts assume the position shown in Fig. 1 35 when the bowl is completely filled.

In the structure shown in Fig. 2, the smoking pipe is formed in the shape of a cigar and the detail structure is slightly different though the principle is the same. In this form of the invention the body 4' has an interiorly threaded end 20 and a tapering tubular member 21 for receiving the tobacco 12. The end toward the mouthpiece 22 is preferably straight and accommodates the coil spring 17, whereby the plate 13' may be properly actuated. Between the tapering tubular member 21 and the body 4' there is a hollow space 23 which prevents the heat from undesirably heating the body 4'. A removable cap 24 is 40 provided, said cap being formed of any desired material, as for instance, briar root, metal or meerschaum. The cap 24 is provided with a threaded portion 25 adapted to be screwed into the threaded portion 20. Also cap 24 is provided 45

50 55

- with an annular interiorly extending flange 26 against which the foraminous member or wire mesh 27 fits. The mouthpiece 22 is screwed on to one end of the body 4', while the cap 24 is screwed 5 into the opposite end. When the parts are in the position shown in Fig. 2, the tobacco may be lighted and during the smoking operation spring 17' will gradually force plate 13' toward the wire mesh 27.
- 10 After the tobacco has been burned and it is desired to re-light the pipe, preferably the cap 24 is removed and a new supply forced into the position shown in Fig. 2 and then cap 24 replaced. It will be understood, of course, that it 15 will not be necessary to completely fill the tobacco chamber unless desired.

I claim:

- A smoking pipe including a bowl having an inturned entrance end and an outlet end provided 20 with a tubular bore extending axially of the bowl

and a smoke outlet passageway of less diameter than said bore leading from said bore intermediate its length, a tobacco chamber of greater diameter than said bore between said bore and said entrance end whereby a shoulder is provided at the juncture of said chamber and said bore, a follower plate in said chamber formed with a central perforated depressed part adapted to extend into said bore when said chamber is filled with tobacco and a radiating flange extending to 10 near the wall of said chamber, said flange resting on said shoulder when said chamber is full of tobacco and a coil spring positioned with one end portion in said bore and the other end portion surrounding said central perforated depressed part of said plate, said spring urging said follower plate toward said entrance end to maintain the ignited portion of the tobacco adjacent said entrance end.

JOHN LANG. 20
